UNITED STATES PATENT OFFICE.

HENRY HUNT, OF GREENVILLE, NEW JERSEY, AND JOHN E. ROLLINGS, OF SPRINGFIELD, MASSACHUSETTS, ASSIGNORS TO THE HARTFORD CARPET COMPANY, OF HARTFORD, CONNECTICUT.

DESIGN FOR A CARPET.

SPECIFICATION forming part of Design No. 13,461, dated November 28, 1882.

Application filed October 18, 1882. Term of patent 3½ years.

To all whom it may concern:

Be it known that we, HENRY HUNT and JOHN E. ROLLINGS, residents, respectively, of Greenville, Hudson county, New Jersey, and of 5 Springfield, in the State of Massachusetts, have invented a new and original Design for Carpets, of which the following is a specification.

This invention relates to a new and original design for carpets and similar fabrics; and it 10 consists in the novel grouping and configuration of figures, hereinafter more fully described.

The accompanying photograph illustrates a face view of a carpet having our new design.

The design, as a whole, consists of a new 15 and original grouping and arrangement of various well-known emblems of Freemasonry.

The design A for the body of the carpet consists, as is fully shown in the accompanying photograph, of rectangles with geometric ornaments, separated by borders resembling tessellated pavement.

The design for the border consists of the system of columns and arches B, as shown, including the pedestals in which the columns 25 rest, and also the surmounting globes and the well-known keystone of the arch, the inclosed fields C and D each consisting of a novel

grouping of emblems, and each including the tessellated pavement at its base, and the field E completing the border, and consisting of a 30 blank field ornamented preferably by any well-known bands and by conventional flower-figures between the arches.

We claim—

1. The design for carpets, consisting of the 35 figures A, substantially as shown.
2. The design for carpets, consisting of the figures B, C, D, and E, substantially as shown and described.
3. The design for carpets, consisting of the 40 figures B, substantially as shown.
4. The design for carpets, consisting of the figures C, substantially as shown.
5. The design for carpets, consisting of the figures D, substantially as shown.

HENRY HUNT.
JOHN E. ROLLINGS.
